UNITED STATES PATENT OFFICE.

GEORGE W. SPALDING, OF WORCESTER, MASSACHUSETTS, ASSIGNOR TO ROYAL
WORCESTER CORSET COMPANY, A CORPORATION OF MASSACHUSETTS.

SEWING-MACHINE GUIDING ATTACHMENT.

Application filed March 8, 1923. Serial No. 623,654.

To all whom it may concern:

Be it known that I, GEORGE W. SPALDING, a citizen of the United States, residing at Worcester, in the county of Worcester and

5 State of Massachusetts, have invented or discovered certain new and useful Improvements in Sewing-Machine Guiding Attachments, of which the following is a specification, reference being had therein to the accompanying drawings.

This invention has for its object to provide an improved arrangement of sewing machine attachments, for use in corset work, and by means of which certain work heretofore requiring three operations may now be performed at a single operation. In the manufacture of corsets the shaped sections of fabric, which are to constitute the body portion of the corset, have heretofore been 10 first stitched together by seams running lengthwise of the corsets. A transverse reinforcing waist band has then been stitched to the inside of the corset at a second operation, and the lengthwise seam has been covered on the inside of the corset, at a third 15 operation, by a covering strip having in-turned edges overlying and enclosing a reinforcing strip. In accordance with the present invention, and by the use of a novel arrangement of sewing machine attachments, this work, heretofore requiring the three operations above referred to, may now be effected at a single operation, as will hereinafter more fully appear.

20 In the accompanying drawings Fig. 1 is a partial front side view, of a three-needle Singer sewing machine equipped with attachments in accordance with the present invention. Fig. 1^a is an enlarged detail view of some of the parts shown in Fig. 1. Fig. 2 is a partial rear side view of the machine shown in Fig. 1. Fig. 3 is a front end view of the same, with the parts beneath the work plate omitted. Fig. 4 is a partial plan view 25 of the work-plate, with the attachments thereon. Fig. 5 is a detail section on line 5—5, Fig. 4. Fig. 6 is an enlarged detail broken out section on line 6—6, Fig. 3. Figs. 7 and 8 illustrate right and left lap-seam guides. Fig. 7^a is a detail view showing the lap seam guide and the spring catch for

removably attaching the same to its supporting bar. Figs. 9 and 10 are enlarged and somewhat diagrammatic views illustrative of the work performed by the use of 55 the invention.

Referring to the drawings, 12 denotes a part of the work-plate of the sewing machine, and 13 denotes a portion of the overhanging arm thereof. This machine comprises a vertically reciprocating needle bar 14 carrying three needles 15, and a presser-bar 16, to which is attached a presser foot 17, properly constructed to co-operate with the three needles referred to. Two of the 60 needles 15 are abreast of each other and the third needle is behind and in a line midway between the two needles in front, as will be understood from Figs. 1 and 3 and the positions of the seams indicated in Figs. 9 and 65 10. This arrangement of the needles affords more room for the arrangement of the complementary loop-taking devices arranged beneath the work-plate. In the present instance the lifting arm 18, which is arranged 70 for co-operation with the usual presser-foot lifter 19, instead of being attached directly to the presser bar, is carried by a sleeve 18^a encircling the said presser bar and having a limited movement independently of said 75 bar. The arm 18 is provided with a rearward extension 20 arranged to be engaged by an inwardly extending lug 21^a at the forward end of the usual lifting lever 21 pivotally mounted on the arm 13, and which lever 80 21 is, in the present instance, intended to be connected with a knee-operated lever, so that the presser-bar may be lifted by the attendant, when desired, without the use of hands. The extension 20 is provided with 85 a pin 22 connected by a coil spring 23 with a screw or pin 24 attached to the head or depending portion 13^a of the arm 13.

Mounted on a slide 25, fitted to the work-plate 12 of the machine, is a double folder 90 and guide 26, adapted to turn in, upwardly, the opposite edges of a strip of fabric 27, the said folder and guide 26 being provided with a guiding slot 28 above the strip slot 26^a, the slot 28 being of a suitable length to 100 receive a reinforcing fabric strip 29 of a proper width to fit between the in-turned

edges 27^a of the fabric strip 27, the said reinforcing fabric strip passing beneath a cross bar 30 joining the inner upper parts of the double folder 26. The fabric strips referred to pass forward to the needles through a guide consisting of a plate 31 attached to the work-plate of the machine and provided at its under side with side lugs 31^a affording a passageway 31^b, between the body of said plate and the work-plate of the machine, for the two combined strips just referred to.

Co-operating with the folder and guides just described is a lap-seam guide 32 preferably removably attached to the lower end of a vertically movable bar 33 adapted to slide up and down in a sleeve 34 carried by a block 35 pivotally attached, as by a screw 36, to the depending portion or head 13^a of the arm 13. The lap-seam guide 32 is arranged rearwardly of the folder and guide 26, and preferably over the rear part of the guide 31. The lap-seam guide 32 is carried by a socketed shank 32^a provided with a spring catch 32^b by which said shank may be removably attached to a pin 33^a on the bar 33. The lap-seam guide may have the guiding grooves therein arranged to form either a right or left guide, as shown in Figs. 7 and 8.

Attached to the top of said bar 33 is a small plate 37 which extends laterally above a pin 38 carried by a lever 39 pivoted at its rear end, at 40, to the head 13^a and connected, between its ends, by a pin 41 and collar 42, to a rod 43 attached at its upper end to a lug 44 carried by the sleeve 18^a encircling the presser bar 16. Encircling the rod 43, between the collar 42 and the lug 44, is a spacing sleeve 45, and a coil spring 46 is interposed between the said collar 42 and a collar or head 45, at the lower end of the rod 43.

The plate 37 is provided with a small lug 37^a connected by a coil spring 47 to a lug 48 attached to the sleeve 34, so that the bar 33, and the lap-seam guide carried by the said bar, will be held yieldingly downward by the said spring 47. By virtue, however, of the lever 39, connected as just described, through the lug 44, rod 43, collar 42 and pin 41, with the sleeve 18^a encircling the presser bar, and which lever 39 is also connected with the indirectly knee-operated lifting lever 21, said bar 33, and the lap-seam guide carried thereby, may be lifted slightly, when desired, without lifting the presser-foot; by reason of the fact that there is normally a slight space between the upper end of the said sleeve 18^a, and the lifting collar 16^a attached to the presser bar, said space permitting a certain amount of lost motion between said sleeve and collar. When, in the full operation of the lifting lever 21, the lost mo-

tion referred to has been taken up, both the presser-bar and the bar 33 carrying the lap-seam guide will be lifted together, as may be necessary in removing or replacing the work.

The pivoted block 35, with which the lap-seam guide is connected, as above described, is normally rigidly fixed to the machine head 13^a by a set nut 49 on a threaded stud 49^a, and when the said set nut is loosened the said block may be turned on its pivot, afforded by the screw 36, so as to swing the lap-seam guide up out of the way when not in use, as denoted by dotted lines in Fig. 1; and the said guide will be retained in its swung-up position by the spring 50 attached to the face plate 51, said spring 50 then bearing against the lower flat end of said block. Attached to the head 13^a is a small block 52 which carries a stop screw 53 arranged to engage the block 35, so that the lap-seam guide may be properly positioned when returned to place after having been swung up out of the way.

In the operation of the invention the fabric strips 27 and 29 pass through the double folder and guide 26, emerging therefrom in the relations and form illustrated in Fig. 9, and in this form move forward beneath the guide plate 31 to the needles. At the same time the corset body sections *a* and *b*, to be joined, are guided to the needles in overlapped relation by the lap seam guide 32, the cut edge of the section *b* having been previously folded under and pressed down, as shown at *b'*, so as to leave no raw edges protruding. The three needles, the positions of which are denoted by the dotted lines *c* in Fig. 9, form three rows of stitches in the work, thus making a neat seam which is reinforced on the inside of the corset by the covering strip composed of the strips 27 and 29, disposed as denoted in Fig. 9, and between which strips 27 and 29 bone pockets *e*, extending lengthwise of the corset, are located. The reinforcing transverse waist band *d*, to be stitched into the corset, will be held by the attendant above the covering strip, composed of the strips 27 and 29, and in which the bone pockets *e* are formed, and beneath the corset body section pieces *a* and *b*, and when, in the progress of the sewing, the reinforcing band *d* arrives at the lap seam guide the latter will be lifted slightly, without disturbing the presser foot, by the attendant, by a slight operation of the lifting lever 21, connected with the lap-seam guide-carrying bar 33, by the parts above hereinbefore described, to let the thickened portion of the work at the waist band pass beneath the said lap-seam guide. Fig. 10 illustrates the relations of the several fabric parts at the waist band.

In making the seams illustrated in Figs. 9 and 10, for one half of a corset, what may be termed a right hand lap-seam guide, as shown in Fig. 7 will be employed; but in stitching the opposite half of the corset, a left hand guide, as shown in Fig. 8, will be used.

It will thus be understood that by means of the invention herein shown and described 10 the joining of corset parts, heretofore requiring three operations, may be effected at a single operation; thereby permitting the work to be performed much more expeditiously and at much less expense than heretofore.

Having thus described my invention I claim and desire to secure by Letters Patent:

1. A sewing machine attachment apparatus, comprising a double folder and guide 20 adapted to be supported on the work-plate of the machine and constructed to guide a strip of fabric and fold in the opposite edges thereof upwardly, said folder and guide having a strip-guiding slot arranged to 25 guide a second strip of fabric above said first-named strip and dispose said last-named strip between the infolded edges of said first-named strip, a second guide on the work-plate for guiding the said strips together to the needles of the machine, and a lap-seam guide adapted to be supported above the machine work-plate and over said last-named guide.

2. The combination with a multiple needle 35 sewing machine, of an attachment apparatus comprising a double folder and guide supported on the work-plate of the machine and constructed to guide a strip of fabric and fold in the opposite edges thereof upwardly, said folder and guide having a strip-guiding slot arranged to guide a second strip of fabric above said first-named strip and dispose said last-named strip between the infolded edges of said first-named strip, a second 40 guide on the work-plate for guiding the said strips together to the needles of the machine, and a yieldingly mounted lap-seam guide supported above the machine work-plate.

50 3. The combination with a multiple needle sewing machine, of an attachment apparatus comprising a double folder and guide supported on the work-plate of the machine and constructed to guide a strip of fabric and fold in the opposite edges thereof upwardly, said folder and guide having a strip-guiding slot arranged to 55 guide a second strip of fabric above said first-named strip and dispose said last-named strip between the infolded edges of said first-named strip, a second guide on the work-plate for guiding the said strips together to the needles of the machine, a lap-seam guide supported above the machine work-plate, and means for lifting said lap-seam guide slightly, when de-

sired, without lifting the machine presser-foot.

4. The combination with a multiple needle sewing machine, of an attachment apparatus comprising a double folder and guide supported on the work-plate of the machine and constructed to guide a strip of fabric and fold in the opposite edges thereof upwardly, 70 said folder and guide having a strip-guiding slot arranged to guide a second strip of fabric above said first-named strip and dispose said last-named strip between the infolded edges of said first-named strip, a second guide on the work-plate for guiding the said strips together to the needles of the 75 machine, a lap-seam guide supported above the machine work-plate, a bar to which said lap-seam guide is attached, a sleeve in which said bar is yieldingly mounted so that it may move vertically, and means for attaching 80 said sleeve to the machine head.

5. The combination with a multiple needle sewing machine, of an attachment apparatus comprising a double folder and guide supported on the work-plate of the machine 90 and constructed to guide a strip of fabric and fold in the opposite edges thereof upwardly, said folder and guide having a strip-guiding slot arranged to guide a second strip of fabric above said first-named strip and dispose said last-named strip between the infolded edges of said first-named strip, 95 a second guide on the work-plate for guiding the said strips together to the needles of the machine, a lap-seam guide supported above the machine work-plate, a bar to which said lap-seam guide is attached, a sleeve in which said bar is yieldingly mounted so that it may move vertically, and a block 100 pivotally attached to the sewing machine head and by which block said sleeve is carried, so that said lap-seam guide may be swung up out of the way when desired.

6. A sewing machine attachment apparatus comprising, in combination, a double folder and guide having inturned members at its opposite edges serving to fold in the opposite edges of a strip of fabric and having also a slot to guide a second strip of fabric between the infolded edges of the first-named strip and direct the composite strip thus formed to the needles of a sewing machine, and a lap-seam guide, supported above the work-plate, for directing two fabric sections, in lapped relation, to 110 the sewing machine needles together with said composite strip.

7. A sewing machine attachment apparatus comprising a double folder and guide adapted to be supported on the work-plate of the machine and constructed to guide a strip of fabric and fold in the opposite edges thereof upwardly, said folder and guide having a strip-guiding slot arranged to 115 guide a second strip of fabric above said

first-named strip and dispose said last-named strip between the in-folded edges of said first-named strip, and a lap-seam guide yieldingly supported above the machine 5 work-plate, combined with means, operated from a presser-foot lifter, whereby said lap-seam guide may be raised slightly without raising the presser-foot of the machine.

8. The combination with a plural needle 10 sewing machine fitted with two needles arranged abreast and a third needle behind and in a line about midway between said abreast needles, of an attachment apparatus comprising a double folder and guide sup- 15 ported on the work-plate of the machine and constructed to guide a strip of fabric and fold in the opposite edges thereof upwardly, said folder and guide having a strip-guiding slot arranged to guide a second 20 strip of fabric above said first-named strip and dispose said last-named strip between the in-folded edges of said first-named strip, a second guide on the work-plate for guid- ing the said strips together to the needles

of the machine, and a lap-seam guide sup- 25 ported above the machine work-plate.

9. The combination with a plural needle 30 sewing machine fitted with two needles ar- ranged abreast and a third needle behind and in a line about midway between said 35 abreast needles, of an attachment apparatus comprising a double folder and guide sup- ported on the work-plate of the machine and constructed to guide a strip of fabric and fold in the opposite edges thereof up- 40 wardly, said folder and guide having a strip- guiding slot arranged to guide a second strip of fabric above said first-named strip and dispose said last-named strip between the in-folded edges of said first-named strip, a 45 second guide on the work-plate for guid- ing the said strips together to the needles of the machine, and a yieldingly mounted lap-seam guide supported above the machine work-plate.

In testimony whereof I affix my signa-
ture.

GEORGE W. SPALDING.
